FRAME

James F. McAdams, West Somerville, Mass., assignor to A. S. Campbell Co., Inc., East Boston, Mass., a corporation of Massachusetts

Application July 14, 1938, Serial No. 219,177

7 Claims. (Cl. 40—125)

This invention relates to sectional frames designed particularly for use on automobile license plates and the object is to provide an improved construction for such a frame permitting it to be easily positioned on the plate or withdrawn therefrom when necessary and yet to be firmly held without rattling.

My invention will be well understood by reference to the following description taken in connection with the accompanying drawing, wherein:

Fig. 1 is a front elevation of a plate having a frame, the construction of which is illustrative of the principles of my invention, applied thereto;

Fig. 2 is a fragmentary plan view, as seen from the inner side, of the elements located at one of the joints of the frame shown in separated position and on a larger scale than Fig. 1;

Fig. 3 is a side elevation and Fig. 4 an end elevation of a clip used in the construction, these views being on a still larger scale;

Fig. 5 is a section on a greatly enlarged scale on the plane of the line 6—6 of Fig. 1 but with the license plate removed; and

Fig. 6 is a section on the line 6—6 of Fig. 1.

Referring to the drawing, I have there shown a license plate 8 having the usual openings 10 by means of which it may be bolted to a carrier bracket on the car. The frame herein shown is of the type which is supported by the plate rather than one which is secured to the car and carries the plate. It may comprise a circuit of sections of hollow tubular form, which herein comprise angular corner sections 12 and alternating straight sections 14, the former telescoping within the latter to provide a wide range of adjusting movement among the sections of the frame to permit it to fit license plates of different sizes and all the sections having an inwardly facing slot 16 or opening to receive the margins of the plate. The sections are of substantial cross section to constitute a frame member and are polished or otherwise attractively finished on their outer surface. Herein I have shown the sections as of circular cross section and split along their inner sides to provide the slots 16.

The slots 16, while narrow, may be of substantially greater width than the normal thickness of the plate 8, and to retain the sections in position on the plate I provide, as in my co-pending application, Serial No. 215,575, filed June 24, 1938, securing devices which grip the edges of the plate and are retained in the tubular sections by virtue of the incurving margins of the latter at either side of the slots 16 which are in effect overhang-

ing flanges. These securing devices in the embodiment shown are spring clips 18 formed of sheet metal and are relatively short as compared with the sections which receive them. Herein I have shown clips at each joint of the frame at the ends of the angular sections 12, which in the example shown telescope within the straight sections 14.

The clip 18 herein shown has generally the form of a split annulus of a size substantially corresponding to the interior diameter of section 12 and which may be slid into the section from the end thereof lying transversely within the same and providing at the split opposed jaw portions 20 normally in contact, as shown in Figs. 4 and 5. Short, outwardly diverging tabs 22 may be provided as extensions of the clip, which tabs, when the clip is in position in the tubular section, as shown in Fig. 5, are located at the slot 16 and form guiding surfaces to receive the edge of the plate 8, which, when pressed in between the jaws 20, is frictionally gripped thereby while the body of the clip is expanded internally of the tubular section 12 (see Fig. 6).

I provide suitable means for retaining the telescoping sections together which, while permitting desired adjusting movement thereof, restricts their free relative longitudinal movement, holding the sections firmly together and preventing rattling. Herein the clips 18 are located at the joints between the several sections and the retaining means is organized as a part of the clips. For this purpose the bodies of the clips may be slit transversely adjacent one end thereof to form the two spring arms 23 having at their extremities outwardly turned fingers 25 spaced inwardly from the position of the jaws 20, the angular distance between these fingers measured around the exterior portion of the clip, that is, the upper portion viewing Figs. 3 and 4, being no greater than the angular distance around the split tubular section 12. The margins of the sections 12 may be provided with notches 27 (see Fig. 2) at one or more points in their length, the sides of these notches being preferably substantially perpendicular to the axial line of the section to provide an abrupt locking shoulder. The fingers 25 spring into and engage these notches, as illustrated in Figs. 5 and 6, the clips thus being positively interlocked against longitudinal movement in the sections 12. The fingers extending through the notches press against the overlying inner wall of the outer section 14 and frictionally hold the latter in position, permitting the section to be forcibly moved when it is desired to adjust the

frame to the plate or remove it therefrom but preventing any casual movement between them.

To secure the frame about the license plate, the clips are first assembled with the sections 12 by 5 being inserted through the open ends thereof and are brought to rest by engagement of the fingers 25 with notches 27. Ordinarily the several sections are assembled in a circuit considerably 10 larger than the plate and collapsed into position thereon. The edges of the plate are introduced between and guided by the flaring tabs 22 and the sections pressed into position. The jaws 20 firmly 15 grip the plate and retain the frame sections in position, the interengaging sections being held together by the action of the fingers 25, as already described. No tools are required. The tabs 22 are inconspicuous in the finished job. The clips 18 may be made of highly resilient material 20 while the material of the sections themselves, as well as their form, may be chosen to give the desired appearance.

I am aware that the invention may be embodied in other specific forms without departing from the spirit or essential attributes thereof, and I 25 therefore desire the present embodiment to be considered in all respects as illustrative and not restrictive; reference being had to the appended claims rather than to the foregoing description to indicate the scope of the invention.

30 I claim:

1. A frame for license plates or the like comprising a circuit of mutually telescoping hollow sections having inturned flanges forming inwardly facing slots to receive the edge of a plate, 35 relatively short members housed in the inner sections having opposed resilient gripping portions presented at the slot adapted to be forced apart by and close in gripping relation on the edge of the plate, the inner sections having openings and 40 the members having inwardly yielding fingers projecting through the openings and engaging the outer sections.

2. A frame for license plates or the like comprising a circuit of mutually telescoping hollow 45 sections having inturned flanges forming inwardly facing slots to receive the edge of a plate, relatively short members housed in the inner sections having opposed resilient gripping portions presented at the slot adapted to be forced apart by and close in gripping relation on the edge of the plate, flanges of the inner sections being 50 notched and the members having outwardly turned, inwardly yieldable fingers locking in the notches and projecting therethrough into engagement with the outer sections.

55 3. A frame for license plates or the like comprising a circuit of mutually telescoping hollow sections having inwardly opening slots of restricted width to receive the edge of the plate and spring clips received within inner sections 60 at the locations of overlapping joints between sec-

tions, the clips adapted to be assembled with the sections through the ends thereof but not to be withdrawn through the slots, the clips having provision for gripping the edge of the plate entered into the slots and also means for frictionally locking together the overlapping portions of the sections.

4. A frame for license plates or the like comprising a circuit of mutually telescoping hollow sections having inwardly opening slots bounded by at least one overhanging flange into which 10 slots the edges of the plate may be entered, and bowed spring clips transversely disposed within inner sections at the location of the overlapping joints between sections, the clips having opposed 15 gripping jaws presented at the slots and outwardly projecting, inwardly yieldable fingers out of alignment with the slots, the inner sections being cut away to pass said fingers for binding engagement of the same with the overlying walls of 20 outer sections.

5. A frame for license plates or the like comprising a circuit of mutually telescoping hollow sections having inwardly opening slots bounded by at least one overhanging flange into which 25 slots the edges of the plate may be entered, and bowed spring clips transversely disposed within inner sections at the location of the overlapping joints between sections, the clips having outwardly turned fingers at their ends, the margins 30 of inner sections having notches in which said fingers are received and through which they pass to engage frictionally the inner wall of an outer section.

6. A frame for license plates or the like comprising a circuit of mutually telescoping hollow sections having inwardly opening slots bounded by at least one overhanging flange into which 40 slots the edges of the plate may be entered, and clips of the general form of short split annuli disposed transversely within inner sections at the 45 location of the overlapping joints between sections, the clips having outwardly projecting fingers resiliently yieldable inwardly, the inner sections being cut away to pass said fingers for binding engagement with the overlying walls of outer sections.

7. A frame for license plates or the like comprising a circuit of mutually telescoping hollow sections having inwardly opening slots of restricted width to receive the edge of the plate, 50 spring clips received within sections adapted to be assembled with the sections through the ends thereof but not to be withdrawn from the slots and having jaws presented at the slots for gripping the edge of the plate entered therethrough, the clips being located at the joints between telescoping sections and constructed to engage one of the sections positively and the other frictionally to restrict the longitudinal movement thereof.

60 JAMES F. McADAMS.
